BATTERY TERMINAL CONNECTOR

Orrin H. Thomas, 2120 W. 4th St.,
Williamsport, Pa. 17701

Filed Nov. 12, 1969, Ser. No. 20,053

Term of patent 14 years

Int. Cl. D13—03

U.S. Cl. D26—1

FIG. 1

FIG. 2

FIG. 4

FIG. 6

FIG. 3

FIG. 5

FIG. 7

FIG. 1 is a perspective view of the battery terminal connector of the present invention.

FIG. 2 is a top plan view.

FIG. 3 is a bottom plan view.

FIG. 4 is a front elevational view.

FIG. 5 is a back elevational view.

FIG. 6 is a side elevational view of one side of the battery terminal connector.

FIG. 7 is a side elevational view of the opposite side from that shown in FIG. 6.

I claim:

The ornamental design for a battery terminal connector, as shown.
